DESIGN FOR A HAND MIRROR OR SIMILAR ARTICLE

Irving Niederman, New York, N. Y.

Application February 20, 1942, Serial No. 105,923

Term of patent 3½ years

To all whom it may concern:

Be it known that I, Irving Niederman, a citizen of the United States, residing at New York, in the county of New York and State of New York, have invented a new, original, and ornamental Design for Hand Mirrors or Similar Articles, of which the following is a specification, reference being had to the accompanying drawing, forming part thereof.

Fig. 1 is a plan view of a hand mirror or similar article showing my new design.

Fig. 2 is a side elevation thereof.

The rear view of the design is identical with the view shown, and the thickness of the design corresponds to the thickness of the material of the backing on the toilet article.

The dominant features of the design reside in the portions shown in full lines.

I claim:

The ornamental design for a hand mirror or similar article, as shown and described.

IRVING NIEDERMAN,
